UNITED STATES PATENT OFFICE.

WILLIAM R. MILBURN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRICAL CONTROLLER.

Application filed August 5, 1922. Serial No. 579,869.

To all whom it may concern:

Be it known that I, WILLIAM R. MILBURN, a citizen of the United States, residing at Milwaukee, in the county of Milwaukee and 5 State of Wisconsin, have invented new and useful Improvements in Electrical Controllers, of which the following is a full, clear, concise, and exact description, reference being had to the accompanying drawing, forming 10 a part of this specification.

This invention relates to electrical controllers and more particularly to manually operable acceleration controllers as for example controllers of the drum type.

15 An object of the invention is that of providing such a controller wherein a portion of the accelerating resistance may be reinclosed temporarily in circuit for protection of the controlled motor under predeterminable conditions of overload, as for 20 example upon stalling of the motor.

Another object is that of providing such a controller requiring for exclusion of such resistance when so reinclosed, such operation 25 of the drum as to enable subsequent starting of the motor only when protected by a value of accelerating resistance above a predetermined minimum value.

Another object is that of providing an 30 exceedingly simple and reliable controller possessing the foregoing characteristics.

Other objects and advantages will herein-after appear.

The invention is applicable to numerous 35 types of drum controller as exemplified in the accompanying drawing wherein Fig. 1 is a diagrammatic illustration of a drum controller of the full reversing type, embodying the invention, while, Fig. 2 is a 40 similar view illustrating an adaptation of the invention to a drum controller adapted to provide dynamic lowering.

Referring first to Fig. 1 of the drawing, 45 the same illustrates a reversible motor including armature A and series field F to be supplied from lines L' and L² and being provided with a series brake release winding B and steps of accelerating resistance R¹ to R⁵. Certain of said resistance steps being 50 moreover capable of use for protection of the motor under given conditions of overload as when in stalled condition, the control of

the foregoing instrumentalities being effected by means of a controller drum indicated generally at D in association with electro-magnetic switches including a resistance switch S and a so-called jamming relay J.

The motor and its directly associated parts including the accelerating resistance, at least so far as involves the ordinary starting functions of the latter, may be of a conventional type whereas the drum with the exception of the lower three fingers thereof and the segments co-operating therewith may be a standard full reversing drum 65 whereby the aforementioned elements warrant no particular description herein.

The resistance switch S is provided with a set of normally open contacts 5 and an additional set 6 of normally closed contacts, 70 the switch being biased by gravity or otherwise to effect closure of the contacts 5 but being on the other hand constrained under normal conditions to maintain said contacts open and the contacts 6 closed, due to continuous energization of its actuating coil 7 under normal conditions. Said switch is further provided with auxiliary maintaining contacts 8.

The circuit of said actuating coil 7 of 80 the switch S is subjected to control by the jamming relay J, the latter being normally closed and provided with a series opening coil 9 and a shunt holding coil 10 the circuit of the latter including a current limiting resistor 11 whereby said holding coil is protected and rendered incapable of effecting opening of the switch when closed. The circuit of the actuating coil 7 of switch S is made through the lowermost contact of 85 the drum D, its co-operating segment being proportioned with reference to the third or maintaining contact to insure maintenance of energization of said coil 7 during movement of the drum to its first or positions.

The maintaining circuit of said actuating coil 7 of switch S and also the circuit of holding coil 10 of relay J are both connected by way of the third drum contact from the bottom, said contact being provided with 100 co-operating segments symmetrically arranged to be in engagement therewith for all on positions of the drum. The second drum contact from the bottom is connected with line

L^2 and is adapted to be at all times in engagement with its associated continuous drum segment to which the aforementioned segments are permanently connected whereby all of said segments are at all times in connection with line L^2 .

- The operation of the controller may be described as follows, the parts being initially in the relative positions illustrated.
- 10 In such relation it is obvious that the motor field and armature are disconnected from both supply lines, the switch S being in its up or normal running position and the relay J being closed.
- 15 Upon movement of the drum to either of its first on positions circuit is established through the motor armature and field in a relation suitable for rotation of the armature in a corresponding direction, the accelerating resistance being all included in circuit, and the various circuit connections being conventional and obvious as far as the fourth drum contact from the bottom of the drum. The motor circuit extends from this point by conductor 12 through the opening coil 9 of relay J thence by conductor 13 through the normally closed contacts 6 of switch S to line L^2 . Progressive movement of the drum through its succeeding positions 20 serves merely to exclude the steps of resistance R' to R^5 progressively for acceleration of the motor in the usual manner.

However, if during positioning of the drum in any on position except the first the motor becomes subjected to overload of a value sufficient to cause opening of the relay J through energization of its actuating winding 9 above the pre-determined value said relay is adapted to open and remain open 25 under the holding action of coil 10, thereby interrupting the energizing circuit of coil 7 of the switch S, whereupon said switch is adapted to drop under its bias thereby shifting the connection of the motor circuit with line L^2 from that formerly traced to the following, viz, from line L^2 through the down contacts 5 of said switch S by conductor 14 to a pre-determined intermediate point in the accelerating resistance R' to R^5 , as for 30 example, the tap between resistance sections R^2 and R^3 , the effect being to include in the motor circuit a portion of the accelerating resistance. The value of the accelerating resistance so included will be the total value 35 of the resistance steps located between the motor and such predetermined point, except that in certain positions of the drum a single step of such resistance may be excluded due to the necessary overlap of the drum 40 contacts and in determining the location of such predetermined point such possible exclusion of a single step of the resistance is of course to be considered.

The aforescribed tripping of the switch S serves additionally to interrupt the main-

taining circuit thereof through opening of its auxiliary contacts 8 whereby upon subsequent closure of the relay J the circuit of actuating coil 7 of said switch S is not re-established automatically but on the contrary said switch S remains in its down position pending return of the drum to off position wherein its lowermost contact is in engagement with the co-operating segment thereof, whereas obviously in the latter case the motor circuit is protected by the total value of the accelerating resistance, and in the former case the motor circuit can be completed only subject to such protection.

Resetting of the device is effected by return of the drum to off position whereby both coils 9 and 10 of relay J are de-energized thus permitting said relay to close. Such action serves to complete the energizing circuit of coil 7 of switch S, whereupon 80 said switch moves to its upper position. The parts are then in the relative positions illustrated and the aforescribed cycle of operations may be repeated.

The various control or pilot circuits although obvious may be traced as follows. The holding circuit of relay J extends from line L' by conductor 15 through current limiting resistance 11 and through coil 10 thence by conductor 16 to the third drum contact counting from the bottom as aforescribed. The circuit of the actuating coil 7 of the switch S extends similarly from line L' by conductor 15 through relay J thence by conductor 17 through said coil 7 90 by conductor 18 to the lowermost contact of the drum. The maintaining circuit for said switch S extends from line L' through the actuating winding 7 thereof as formerly traced then by conductor 19 through the auxiliary contacts 8 and by conductors 20 and 16 to the third drum contact as formerly described.

Considering now Fig. 2 of the drawing it is apparent that the switch S and relay J are precisely similar to the corresponding elements of the construction just described, whereas the functions and circuit connections of said switches are also identical or similar. The motor and its connections, however, have been modified in a conventional manner to adapt the same to effect dynamic lowering of overhauling loads, whereas the structure of the drum has been modified to provide for such dynamic lowering and also to restrict the action of the resistance switch S and the jamming relay J to that portion of the operative cycle wherein the right hand or hoist side of the drum is active.

Thus during the hoisting portion of the operative cycle the action of the controller is in all respects similar to that just described and hence appears to warrant no further description or explanation herein.

On the other hand during lowering these particular features are inactive having in fact no function to perform, the dynamic lowering provided by the drum being merely a conventional and well known form of such lowering action.

Here it may be observed that the afore-described protective devices are applicable to numerous forms of drum controller other than those herein illustrated and described, the specific examples herein given being only typical.

Further it is to be noted that the point of connection of conductor 14 to the accelerating resistance is preferably so selected that upon stalling of the motor the current to which the same is subjected while in stalled condition shall not exceed the normal current by much more than 25 percent, although of course this value also is capable of variation and preselection by the means disclosed.

What I claim as new and desire to secure by Letters Patent is:

1. A controller for electric motors comprising regulating resistance for the motor, means for excluding and including said resistance, and means acting independently of the former means for insuring inclusion of a predetermined value of said resistance in circuit with the motor under predetermined conditions before or after completion of said resistance excluding operation and for maintaining said predetermined value of resistance in circuit pending a given subsequent operation of said first mentioned means.

2. A controller for electric motors comprising regulating resistance for the motor, means for excluding and including portions of said resistance, and means acting independently of the former means for automatically including a predetermined value of said resistance in circuit with the motor under predetermined load conditions before or after completion of said resistance excluding operation and for maintaining said predetermined value of resistance in circuit pending a given reverse operation of said first mentioned means.

3. A controller for electric motors comprising regulating resistance for the motor, a drum controller to commutate said resistance, means adapted to provide a portion of said resistance in circuit with the motor under predetermined load conditions, and associated means requiring operation of the drum to include at least a given value of said resistance in order to neutralize said former means.

4. The combination with a reversible motor, regulating resistance and a reversing drum controller for commutating said resistance, of a switch providing for inclusion of a regulable value of such resistance in the motor circuit automatically under given load

conditions, said drum controller and said switch having associated means providing for interruption of the resistance control by said switch but only upon such actuation of the drum as to insure a given value of said resistance in the motor circuit.

5. The combination with a reversible motor, regulating resistance and a reversing drum controller for commutating said resistance, of an electroresponsive switch having an operating winding to be energized under normal conditions for holding said switch in a given position, said switch being biased to a different position for commutating the motor circuit to include therein a portion of the regulating resistance irrespective of positioning of the drum to exclude such portion, and a relay for interrupting the energizing circuit of said switch under given load conditions.

6. The combination with a reversible motor, regulating resistance and a reversing drum controller for commutating said resistance, of an electroresponsive switch having an operating winding to be energized under normal conditions for holding said switch in a given position, said switch being biased to a different position for commutating the motor circuit to include therein a portion of the regulating resistance irrespective of positioning of the drum to exclude such portion, a relay to interrupt the energizing circuit of said switch under given load conditions and means for maintaining said circuit de-energized pending such operation of the drum as to insure at least a given value of resistance in the motor circuit.

7. In a dynamic lowering controller for electric motors, the combination with the motor, regulating resistance and a control drum therefor, of a switch biased to effect commutation of the motor circuit to include a portion of the regulating resistance irrespective of positioning of the drum to exclude such portion, an operating coil for said switch to be energized under normal conditions for preponderating such bias, a relay to open and effect de-energization of said operating coil under given load conditions of the motor and a holding coil for maintaining said relay open, said drum having associated means providing for de-energization of said holding coil but only upon movement of the drum out of its first position toward its full off position.

8. The combination with an electric motor, regulating resistance therefor, a drum controller for commutating said resistance, and a switch adapted to automatically insure inclusion of a predetermined value of said resistance under given load conditions irrespective of the position of said drum controller and for maintaining said predetermined value of resistance in circuit pending

reinclusion of a given amount of resistance in circuit by said drum controller.

9. The combination with an electric motor, regulating resistance therefor, a drum controller for commutating said resistance, a switch having normally closed contacts in series with all of said resistance and normally open contacts adapted when closed

to be in series with a portion of said resistance, and a jamming relay for effecting opening of said first mentioned contacts and closure of said last mentioned contacts under given load conditions. 10

In witness whereof, I have hereunto subscribed my name.

WILLIAM R. MILBURN.
